PAPER BOX

Alexander H. Dreux and Joseph N. Royal, Buffalo,
N. Y., assignors to F. N. Burt Company, Lim-
ited, Toronto, Ontario, Canada, a corporation
of Ontario, Canada

Application December 7, 1934, Serial No. 756,447

7 Claims. (Cl. 229—6)

This invention relates to containers for finely divided solid material and especially to face powder boxes utilizing an inner powder receptacle or powder drum which is to be filled with the powder and inserted in the base of the box.

One important object of the invention is the provision of a simple and practical construction by which discharge of powder from the box is confined to the regular discharge opening of the box, its egress from the box through the joints of the latter being greatly minimized or entirely prevented.

Another object of the invention is the provision of a practical and efficient construction of the box parts which lends itself to the rapid production of siftless face powder boxes by automatic machinery.

Another important object of the invention is the provision of a simple and efficient construction of powder container drum which itself is highly promotive of the securement of a siftless box and which may readily and easily be inserted in place in the base notwithstanding variations of diameter between the drum and the base in which it interfits.

Another important object of the invention is the provision of an efficient packing material for face powder boxes of the character described.

Another object of the invention is the provision of a simple and practical method for making non-sifting face powder boxes.

Another important object of the invention is the provision of a practical construction of face powder box in which the powder material is adapted to cooperate to form a packing for arresting exit of powder from the box through the joints.

It is a further object to provide a means of overcoming the inherent variation in the size, or more specifically the diameter of the parts manufactured on high-speed production machines with particular regard to those parts that must fit within each other in the assembly of the complete parts.

It is a further object to provide a means of overcoming the variation in finished part size, which is occasioned by variations in the thickness of the several plies of stock used in making the parts of a round, square, rectangular, or multi-sided box or container.

Other objects of the invention will in part be obvious and will in part appear hereinafter.

The invention accordingly comprises the several steps and the relation and order of one or

more of such steps with respect to each of the others, and the article possessing the features, properties, and the relation of elements, which are exemplified in the following detailed disclosure, and the scope of the application of which will be indicated in the claims.

For a fuller understanding of the nature and objects of the invention reference should be had to the following detailed description taken in connection with the accompanying drawing, in which:

Fig. 1 is a perspective view, partly sectional, of a face powder box with its cover and illustrating an embodiment of the invention;

Fig. 2 is a vertical section through the box of Fig. 1;

Fig. 3 is an enlarged vertical section of a portion of the box, the dotted lines illustrating the drum before being seated in position in the base of the box;

Fig. 4 is a view of the base, the cover and drum, each in perspective and in separated relation;

Fig. 5 is a plan view illustrating a ring made of a coiled strip of paper and which may be utilized either in the base or in the drum, the paper strip being thicker than that which may be employed; and

Fig. 6 is a detailed sectional view through one side of the box, somewhat enlarged over Fig. 2.

Referring now more specifically to the drawing, the base of the box is indicated at A, the cover or top at B and the drum at C. The base has a head 1 and an upstanding flange or ring 2. Similarly, the cover B has a head 3, and a depending flange or ring 4 and the head 3 may be domed as illustrated. The drum provides a container for reception of face powder and has a flange or ring 5 and an overlying head 6. In the present invention the head 6 is preferably made of a readily frangible sheet material such as tissue paper or any of the well known thin, translucent sheet materials. A sufficiently large sheet is selected and its margin or edge is folded onto the outside face of the drum-ring 45 or flange 5, the fold being secured by an overlying strip of thin cover paper 7 extending continuously around the drum ring 5 and pasted to said ring. The cover strip not only secures the fold of the drum head 6; it also covers any small wrinkles in the fold and provides a relatively smooth, unwrinkled outer side face of the drum flange or ring 5. For convenience of the powder maker, the base A, cover B and drum C are provided as separate units. The drum C

- is open at its end opposite or remote from the head 6, and the powder maker places it with its open end up so it may easily be filled with the powder. Thereupon after filling, the drum may 5 be inserted in the base A, the flange or ring 2 becoming an outer ring and the flange or ring 5 becoming an inner ring. In this manner the base A not only forms a closure for the filling opening of the powder containing drum C, but it 10 also forms a receptacle and housing in which the drum is received. For finishing the base flange 2, and securing it to the head 1, a thin strip of ornamental paper or other material 8 may be wound onto the flange 2 and will be folded over 15 the open edge of this flange and around onto the head 1, and adhesively secured inside and outside the base A. In like manner a finishing strip 9 may be affixed to the cover B, and entirely over the head 3.
- 20 The present invention is of advantage in hand made boxes inasmuch as among other factors, it promotes quick assembly of the parts and the making of a non-sifting face powder box, but it possesses very important advantages when utilized in paper boxes the parts of which are made by automatic machinery operating at high speed. One of the most important objects sought for in 25 a face powder box is that it shall not "sift"; that it shall be "siftless", meaning that the powdered contents shall be retained in the box and not sift out through its joints. As tending to avoid sifting, the diameters of the drum flange 5 and the base flange 2 have heretofore been of relative size to obtain as tight a fit as 30 possible consistent with the requirement that one must be inserted in the other in telescopic relation. The result has been that in many cases the insertion may not be effected at all or only with the greatest care, thus leading to great 35 loss of time and waste of materials, and increasing production costs and slowing down output. The high speed machines are thus not effective to produce merchantable boxes in the quantities for which they are designed. They may run at 40 high speed, but much of the product has to be rejected. Also, various supplemental operations at substantial cost have been resorted to, none of which has been satisfactory, especially in 45 making a satisfactory face powder box capable of being marketed at low cost, as for instance required in the ten-cent stores.

Dependence upon the fit of the drum flange and the base flange for tightness has been entirely unsatisfactory. Supplemental operations 50 of the past have been equally unsatisfactory in preventing or minimizing "sifting" and have but added to operations and to cost.

An important aspect of the present invention concerns the relative diameters of the inner and 55 outer rings or walls provided for the base and drum respectively.

An important related feature of the present invention resides in providing an inner drum ring or flange of appreciably smaller outer diameter than the internal diameter of the outer base-ring, thus allowing a loose fit between the rings notwithstanding variation of moisture content or thickness of stock material, so that free entry of one ring into the other is readily permitted under all conditions, a space being thus always provided between the two rings in their telescopic relation to each other. The importance of this will become manifest from the following considerations:

75 In modern, high speed, automatic box ma-

chines these rings are formed by coiling or winding relatively stiff, thin paper stock on rotating mandrels having fixed diameters. It has been the common practice to depend upon the closeness or tightness of the fit of the outer diameter of the drum ring, or flange, against the inner diameter of the base ring, or flange, to hold the powder in the box and to prevent sifting, i. e., escape of the finely divided particles out of the drum, and accumulation of substantial amounts in loose condition, on the top of the drum head and beneath the cover, especially before the cover is removed. It is a difference in diameter of but a few thousandths of an inch between the fit of the rings or flanges on each other that may result in sufficient looseness to sift powder or one that is so tight that these rings cannot be made to telescope. Drum rings or flanges are commonly made of two, three or more ply light weight paper, and while on the whole they are relatively stiff, they may have some flexibility, dependent on the paper stock and the number of plies employed. As has been before explained, the margin of the head 6 is folded down and a cover strip 1 may be applied. Accordingly any predetermined outside diameter of the drum ring is dependent on several factors including the thickness of the paper stock and of the glue which may be employed to hold the plies together and to secure the cover strip. Assuming it to be the practice to purchase nine and one-half point card-middling stock from which to coil a four-ply drum ring but such stock averages ten and one-half points in thickness instead of nine and one-half points, eight thousandths of an inch will be added to the outer diameter of the drum. And it is not uncommon to find even more variation, eight point to eleven point, affecting the outer diameter of the drum ring in paper stock of this small 20 caliper. Not only is there this unavoidable variation in thickness or caliper of the paper stock which will result in a non-telescoping drum-ring. There are also variations in thickness due to moisture content of the stock, its thickness being one caliper when made and a different thickness when assembled drum to base. By providing the drum-ring of appreciably smaller outer diameter than the internal diameter of the base ring and having the loose fit as hereinbefore 25 stated, the objections dependent on variations of stock-thickness are very substantially avoided and the production of siftless boxes at high speed on automatic machinery is greatly promoted, and this is especially so when taken in conjunction with the feature of the invention which arrests the escape of powder notwithstanding the rings are of appreciably different diameter as aforesaid. As illustrated in the drawing, the drum ring 5 is formed of relatively stiff thin 30 paper stock coiled in a plurality of plies into ring formation as shown in Fig. 5. Also it is to be understood that the ring or flange of the base may be constructed of a similarly coiled paper strip. Another important aspect of the invention relates to adjusting or compensating for the looseness of fit between the drum ring 5, and the base flange 2 so as to attain the improvements due to the loose fit (as for instance free entry of one ring into another; avoidance of objections on account of variation in caliper of stock, whether due to moisture or to unavoidable variation in original stock material) and nevertheless to promote the anti-sift features of the 35 powder box. To this end a means is provided 40

which is disposed and adapted to bring the diameters of the base flange or ring and the drum flange or ring to relative size producing a tight fit in the joint between the base and drum. Initially this means may be mounted either on the base or on the drum, but it is preferably initially mounted on the drum. It includes plastic, joint-packing or caulking material 10 which is cooperable to join the flanges or rings of the base and the drum together and, in the embodiment illustrated lies between said rings and is in the form of a continuous circumferential bead or ring around the drum ring 5. It is of narrow width relative to that of the box rings and is spaced apart from the end 11 of the drum. It is preferably located close to the head 6 of the drum and overlies the fold thereof. It adds to the stiffness of the drum and hence tends to hold the head 6 taut. When initially on the outer face of the separate drum flange or the inner face of the separate base flange, it protrudes therefrom and its protruding portion is curved or convexed outwardly in cross-section, as clearly seen in Figs. 3 and 4, and forms a relatively narrow strip or bead projecting laterally of the flange.

The material of the ring or bead 10 is relatively soft and readily shearable and compressible and it is adapted to be altered in thickness by contacting with the base flange or ring under the force of seating the drum ring in its operable position in the base ring or flange. In the operation of telescoping the flanges 2 and 5, the bead 10 is carried by one flange into such position that the other flange, forced to telescopic relation with the flange carrying the bead 10, will cause said bead tightly to pack or caulk the space between said flanges.

A suitable plastic material for the ring 10 is some species of solid wax or wax like substance, as blended wax. Preferably the ring 10 is bonded to the drum or base, whichever is the initial carrier, in a melted state. Under mild heat it may be bonded to the other ring after telescopic insertion in the other ring. The ring 10 forms an exterior layer on the box part.

In some instances it is desirable to utilize for the ring 10 a species of plastic, as wax, to which due to its tackiness particles of the face powder 50 will adhere, thus anchoring the powder particles to the wax substance, and to the paper—these particles tending to block any fine interstices in the wax packing and forming a packing of powdered material.

It is to be understood that either the base or drum having the wax or plastic ring 10 mounted thereon is utilizable alone as a separate article of manufacture for any convenient use. In carrying out the method, the base flanges or rings are formed separately from the drum flanges or rings, and of relative size loosely to interfit. After the paper rings are made the interfitting face of one ring is provided with a plastic shoulder or conforming ring, 60 as the packing ring 10 of wax or other plastic material which is thicker than the maximum space between said rings when the rings are in interfitting relation. This may be done by directing onto the drum while on its mandrel 65 a stream of the melted, plastic material. This also bonds the plastic to the drum. Thereafter one ring, after being filled with powder, is pressed into the other and by the pressing or driving operation the conforming ring or shoulder is driven into position tightly packing the

joint between the rings. After the drums are filled and inserted in the bases, a slight application of heat to the outside of the bases causes the plastic ring to bond to the flange of the base, thus also making a hermetic seal.

By employing a wax like material having a relatively low melting point, as for instance paraffine, the wax like ring 10 easily chills and solidifies so it may readily be handled, the ring offering a convenient shoulder or handle to lessen slip of the fingers. An important function of the plastic is to interrupt and form a non-sifting powder-barrier in the joint between the rings. It fills the space between the rings and also will mold itself into all irregularities 15 of the space, as for instance formed by the ends or edges of the cover-paper, the folded margin of the head 6, and other irregularities. The plastic ring 10 is of a substance relatively soft and solid at room temperature, as for instance 20 some species of wax, and the melting point of this substance is considerably lower than the point of inflammability or charring of the paper so that the substance may be bonded to the paper by the application of heat without injur- 25 ing the paper. Also the substance may have some degree of viscosity or tackiness in the solid state so that particles of powder may adhere to the packing.

It is to be understood that among the substances of which the ring 10 may be made are the various waxes, such as paraffine, beeswax, halowax, carnauba, spermaceti, cerese or combinations of these waxes, or mixture of chlorodiphenyl and sulphur, the former comprising 30 the larger percentage of the mixture. Bitumens or resinous materials might be used, or combination of bitumens and resins.

In bases having non-flaring open ends, the diameter of the plastic ring 10 on the drum ring 40 should be larger than that of the open end of the base ring so as to either be compressed and slide over the edge of said open end or to have a portion sheared off from the plastic ring in the operation of telescoping the two rings. In 45 either case tight interfitting of the ring 10 in the joint is effected.

It is to be understood that the boxes need not be round as illustrated, but may be oval or polygonal or of any shape appropriate for embodying the invention. Accordingly it is to be understood that the terms "ring", "flange", etc. herein employed cover and comprehend similar walls for the box parts whether they are circular, oval, square, hexagonal, or other shapes.

It is to be understood that the packing or caulking bead 10 may in some instances be applied to the base flange instead of to the drum flange, or each of these parts may have an individual bead. The bead applied to the drum is 60 more practical however and is to be preferred. It is also to be understood that, whereas a coiled or multi-ply flange is illustrated the invention is available for flanges of single ply formation. Thin paper stock is preferred for the 65 material of the flanges, but it is to be understood that the invention is available for boxes or box-flanges made of other materials, as pasteboard, card middle stock, and the like. Also in some instances the conforming ring or bead 10 70 is colored in contrast to the color of the flange to which it is applied, thus enabling its structure and arrangement to be more readily observed, and any defects noted and remedied.

It is also to be understood that, in some as- 75

pects of the invention, the shape of the caulking or packing may vary from continuous ring form, an important feature being to close the joint between the base and drum regardless of 5 the shape of packing required to do so.

Since certain changes in carrying out the above process, and certain modifications in the article which embody the invention may be made without departing from its scope, it is intended 10 that all matter contained in the above description or shown in the accompanying drawing shall be interpreted as illustrative and not in a limiting sense.

Having described our invention, what we claim 15 as new and desire to secure by Letters Patent is:

1. A box of the character described including, in combination, a box part including a powder container having a filling opening at one end and being closed at its opposite end, a box part including a receptacle for telescopically receiving said container to provide a space between the receptacle and container, whereby said container and receptacle are cooperable for being shifted to telescopic assembly relation one in the other 20 to close said powder container, and means, including a bead of relatively soft wax-like material shiftable with one of said box parts, and cooperable to bridge the space between said parts and to restrain the escape of powder through 25 said space in the assembled relation of said parts.

2. A box of the character described including, in combination, a box part including a powder container having a filling opening at one end and being closed at its opposite end, a box part including a receptacle for telescopically receiving said container to provide a space between the receptacle and container, whereby said container and receptacle are cooperable for being shifted to and from telescopic assembly relation 30 one in the other to open and close said powder container, and means, including a bead of relatively soft wax-like material bonded to the outer surface of said powder container and spaced 35 from one end thereof and being cooperable to bridge the space between said powder container and said receptacle to restrain escape of powder.

3. A box of the character described including, in combination, a box part including a powder container having a filling opening at one end, a frangible closure head at the opposite end of said container and having an angularly disposed attaching flange by which it is attached to the container, a box part including a receptacle telescopically receiving said container to provide a space between the receptacle and container whereby said container and receptacle are cooperable for being shifted to telescopic assembly relation one in the other to close said powder container, and means including a bead of relatively soft wax-like material attached to and extending around said powder container directly opposite to said attaching flange and being cooperable to bridge the space between said parts 45 and to restrain the escape of powder.

4. A box of the character described including, in combination, a powder container having a filling opening at one end, a frangible closure head at its opposite end, said container including a strip of thin paper coiled into a multi-ply 5 ring to form the lateral container wall, packing means including a packing ring of wax encircling said coiled ring and cooperable to reinforce the latter, a receptacle for telescopically receiving said container, said container and receptacle 10 cooperable for being shifted to or from telescopic assembly relation one in the other to close or open said powder container, and to dispose said wax ring either out of said receptacle or in the latter to provide a packing between the receptacle and container.

5. An anti-sift powder box including, in combination, two box parts, including a powder containing drum and a base or closure part for the drum, said drum and closure parts having side 20 flanges, one of which is of materially less diameter than the other whereby one box part will loosely telescope within the other part with a material space therebetween, said powder containing drum being closed at its upper end and having a filling opening at its lower end and said closure part being positioned when assembled for closing said lower filling opening of the drum, and a caulking device including a bead of plastic wax-like material positioned between 25 said flanges and extending entirely therearound and filling and caulking the space therebetween so as to form an anti-sift joint.

6. An anti-sift powder box including, in combination, two box parts including a powder containing drum and a base or closure part for the drum, said drum and closure parts having side flanges one of which is of materially less diameter than the other whereby one box part will loosely telescope within the other part with a material space therebetween, said powder containing drum being closed at its upper end and having a filling opening at its lower end and said closure part being positioned when assembled for closing said lower filling opening of the drum, and a caulking device including a bead 40 of plastic wax-like material positioned between 45 said flanges and extending entirely therearound and filling and caulking the space therebetween so as to form an anti-sift joint, said wax-like 50 bead being bonded to the surface of one of said side flanges, and prior to insertion in caulking position, being thicker than said space between the flanges so as to fit tightly in caulking position when forced therein.

7. A powder-containing drum for a powder box, said drum having a side flange or wall and having a frangible closure head attached to one end thereof, the opposite end of said drum having a filling opening, and a caulking bead of waxlike material attached to and protruding outwardly from the outer side of said flange and extending around the drum.
